UNITED STATES PATENT OFFICE.

WILLARD B. PORTER, OF SALEM, MASSACHUSETTS.

DESIGN FOR A PIPE.

SPECIFICATION forming part of Design No. 37,244, dated November 22, 1904.

Application filed October 26, 1904. Serial No. 230,147. Term of patent 3½ years.

To all whom it may concern:

Be it known that I, WILLARD B. PORTER, a citizen of the United States, residing at Salem, in the county of Essex and State of Massachusetts, have invented a new, original, and ornamental Design for a Pipe, of which the following is a specification, reference being had to the accompanying drawings, forming part thereof.

The figures represent four views of a pipe, showing my new design. Figure No. 1 rep-

resents the right side view; Fig. No. 2, the left side view; Fig. No. 3, the front view; Fig. No. 4, the rear view.

What I claim as new, and desire to secure by Letters Patent, is—

The ornamental design for a pipe, as shown.

WILLARD B. PORTER.
